TOY FIREARM

Vito Damico, Chicago, Ill.

Application December 13, 1932. Serial No. 647,048

2 Claims. (Cl. 124—14)

This invention relates to toy fire arms and has particular reference to a toy gun of the type employed for "shooting" rubber bands.

The object of this invention is to provide a toy gun of the character above mentioned that is extremely simple in construction and operation, consisting of a minimum number of parts and accordingly can be cheaply made and retailed at a nominal cost.

10 The invention together with its numerous objects and advantages will be best understood from a study of the following description, taken in connection with the accompanying drawing wherein:

15 Figure 1 is a side elevational view of the gun. Figure 2 is a top plan view thereof.

Figure 3 is a fragmentary elevational view illustrating certain details of construction to be hereinafter more fully referred to.

20 Referring to the drawing by reference numerals it will be seen that the toy gun comprises a barrel 5, a handle 6, guard 7 and what may be termed a hammer chamber 8. In this connection it is to be noted that the toy fire arm is 25 designed to simulate, in a general way, a pistol. Arranged in the chamber 8 is a disk 9 provided on its periphery with a circular series of spaced fingers 10. At its center the disk 9 is provided with an opening 11 of relatively large diameter 30 to accommodate a pivot 12 that is fixed within the chamber and is of a relatively small diameter so that the disk 9 is engaged with the pivot in a manner to permit of a shifting of the disk in any desired plane radial to the pivot 12. The 35 disk 9 being thus freely shiftable it will be seen that the fingers 10 thereon may be readily brought into engagement with a stop 13 in a manner to prevent casual rotation of the disk 9 in a clockwise direction.

40 At its free end the barrel 5 is provided with a notch 14 and the rubber bands 15 are engaged with the notch 14 and with the periphery of the disk 9 between the fingers 10 in a manner to hold the bands 15 in taut or stretched condition so as to be successively "shot" as the disk 45 9 is rotated in a clockwise direction.

The use and operation of the invention is 50 thought apparent. In loading the gun one of the fingers 10 is engaged with the stop 13 in the manner shown in Figure 3 and the bands 15 are then engaged with the notch 14 and the disk 9 in the manner shown in Figure 1. With the gun thus "loaded" a rapid firing of the gun may be 55 readily accomplished by shifting the disk 9 toward the left in Figure 3 so as to move the finger 10 engaged with the stop 13 out of engagement with said stop. The disk 9 will then be caused to rotate rapidly in a clockwise direction and the bands 15 thus fired in rapid succession.

60 Preferably, the pistol is made of wood and con-

sists of two identical sections each of which is cut and shaped to provide for the barrel 5, guard 7 and handle 6 and these sections are secured together through the medium of the pivot 12 and stop 13 which are in the nature of rivets and also 65 by additional rivets 16. For the purpose of forming the chamber 8 the sections of the gun are recessed in the region of the guard 7 and at the junction of the barrel 5 and handle 6 in a manner clearly suggested in Figure 3.

70 From the foregoing it will be seen that I have provided a toy firearm of this character which may be economically constructed; and consists of a minimum number of parts; and which provides for the rapid firing of a number of rubber 75 bands.

Even though I have herein shown and described the preferred embodiment of the invention, it is to be understood that the same is susceptible of further changes, modifications and improvements 80 coming within the scope of the appended claims.

Having thus described my invention, what I claim as new is:

1. A toy pistol adapted to project rubber bands comprising two complementary sections adapted to 85 be arranged in flat parallel relation, rivets securing the sections together, said sections having corresponding portions thereof recessed to provide a chamber, through which two of said rivets extend, a disk arranged in the chamber and provided in its center with a relatively large opening 90 for accommodating one of said two rivets, and being also provided on its periphery with radially projecting fingers to be engaged by the rubber bands, and, upon shifting of said disk relative 95 to the said one of said two rivets, to engage the other one of said two rivets for retarding rotation of said disk.

2. In a toy gun to shoot elastic bands, a fixed pivot, a circular disk having a centrally located 100 circular opening accommodating said pivot, said opening being of a diameter materially greater than the diameter of said pivot, said disk being also provided with peripheral lugs to be each engaged with one end of a band, with the lower 105 portion of the disk serving as a trigger to manually actuate the disk and release the bands, and a fixed stop with which said lugs successively engage as the disk rotates and toward which said disk is normally urged with the pulling pressure 110 of the bands on the lugs.

VITO DAMICO.
